STOPPING MECHANISM

Thomas H. Seely, Melrose, Mass., assignor to
United Shoe Machinery Corporation, Paterson,
N. J., a corporation of New Jersey

Original application February 28, 1927, Serial No.
171,388. Divided and this application Febru-
ary 27, 1930. Serial No. 431,896

12 Claims. (Cl. 192—148)

This invention relates to mechanisms for controlling the operations of machines which are to be driven through one or more rapid cycles and stopped at a predetermined point in a cycle. The invention is herein illustrated as embodied in a hand method lasting machine such, for example, as that disclosed in United States Letters Patent No. 1,623,135, granted April 5, 1927, on my application, and in United States Letters Patent No. 10 1,777,382, granted Oct. 7, 1930, on my application, of which the present application is a division. It is to be understood, however, that the invention is not restricted in its application to machines of this type but may be utilized in other machines having adjustable heads.

In hand method lasting machines, the stopping mechanism is located in the head of the machine which is ordinarily adjustable vertically on a supporting column. The stopping mechanism is 20 controlled by a trip rod which is adjustably secured to a treadle and when the head is adjusted to the height of the operator, the treadle and trip rod have to be disconnected and the operative relation of the trip rod to the stop mechanism is 25 disturbed, thus necessitating a careful readjustment of the trip rod into its proper position relatively to the stop mechanism.

It is an object of this invention to provide 30 means whereby such readjustment may be avoided. Accordingly, a feature of the invention consists in an organization including means for maintaining a manually controlled member in constant relation to the head of the machine when the head is adjusted. In the illustrated machine, 35 the means for maintaining a manually controlled member in constant relation to the head comprises an arm clamped at one end to the trip rod and having a slot in its upwardly extending arm which engages a fixed pin on the frame, and an 40 adjusting screw extending into the slot and engaging the pin to limit the depression of the arm and the rod. This construction eliminates the necessity of readjusting the rod in its proper relation to the stop mechanism before tightening the 45 clamping connection between the treadle and the trip rod, thus simplifying the operation of adjusting the head and saving time.

In addition to the above features, the present 50 invention includes other novel features and combinations of parts all of which will be hereinafter fully described in connection with the accompanying drawing which shows one mechanical embodiment of the various new features and 55 novel combinations of parts.

In the drawing, Fig. 1 is a view in side elevation, partly broken away and partly in section, of a machine embodying the present invention;

Fig. 2 is a detail in front elevation, partly in section, of the invention; and

Fig. 3 is an enlarged detail view showing the spring for releasing the brake.

Referring to Fig. 1 of the drawing, 4 represents the head of a hand method lasting machine 6 having a main shaft 6 to one end of which is keyed a pulley 7. Secured to the shaft 6 are various cams and gears which actuate the fastening inserting mechanism 8 and the lasting instrumentalities 10. Reference may be had to my 70 above-mentioned Letters Patent for a more detailed description of the above-mentioned mechanism.

As shown in Fig. 1, the machine is provided with the usual counter-shaft 54 which is continuously driven from a source of power and has fixed thereto a friction disk 56. A co-operating disk 58 is forced toward the disk 56 by a wedge 60 raised by a treadle lever 62. A pulley 64 fixed to the disk 58 is belted to the pulley 7. The machine is preferably provided, as shown in Figs. 1 and 2, with stop mechanism similar to that disclosed in Letters Patent of the United States No. 1,356,406, granted October 19, 1920, on my application. This mechanism comprises a brake 75 shoe 66 lined with a piece of leather 68 which is formed at one end as a hook to engage one end of the shoe 66 and is forced against the inner face of the rim of the pulley 7 to arrest movement of the shaft 6 at a predetermined point in 90 the cycle. The cycle 66 is pivoted to a lever 70 which is acted upon to operate the shoe by a spring detent 72 mounted on a member 74 which is arranged to swing on an eccentric 76 on the shaft 6. A roll 78 on the member 74 engages a 95 beveled end on a vertically movable trip rod 80. At the proper time in the cycle, provided the trip rod is in its normal depressed position, the eccentric 76 moves the member 74 radially while the roll 78 is in contact with the beveled end of 100 the trip rod 80, forcing the detent 72 against the lever 70 and applying the brake.

The trip rod 80 is connected (Fig. 1) by a split clamp operated by a screw 82 to a member 84 which is pivoted at 86 to the treadle lever 62. 105 Depression of the treadle to engage the friction disks 56, 58 will concurrently lift the rod 80 and cause its beveled end (Fig. 2) to swing the member 74 about its operating eccentric 76 and release the detent 72 from the end of the lever 110

70, the brake shoe being then raised by a suitable spring 79 (Fig. 3). The beveled end of the trip rod 80 is maintained in operative relation to the roll 78 when the screw 82 is released to permit 5 the machine head to be raised or lowered. For this purpose a sleeve 88 has a sliding fit on the rod 80 and provides a long bearing therefor to minimize wear. The upper end of the sleeve is 10 conical and engages a hole in a portion 90 of the frame, through which the rod extends, to centralize the rod in the hole. On the lower end of the sleeve is a frame-like portion 91 through the lower end of which the rod 80 passes and between which and an adjustable collar 92 is arranged 15 a spring 93 to depress the rod and maintain the sleeve 88 pressed upwardly into the hole in the frame. Within the frame 91 an arm 94 is clamped to the rod and has a slot 95 in its upwardly extending end which engages a fixed 20 pin 96 on the frame. An adjusting screw 97 engages the pin and limits depression of the arm 94 and the rod 80. This pin-and-slot connection also prevents rotation of the rod 80 so that the operative relation of the beveled end of the rod 25 to the roll 78 is maintained when the screw 82 is loosened. By merely loosening the screw 82 and a clamp screw 98 (Fig. 1), which holds the neck of the machine head in the column 100, a screw 99 may be turned to adjust the head vertically, it being understood that a splined 30 connection between the rock-shaft 101 and a knee operated lever (not shown), and between the sleeve 103 and the arm 105, permits movement of the rock-shaft and sleeve with the head.

35 Having thus described my invention, what I claim as new and desire to secure by Letters Patent of the United States is:

1. In a power-operated machine, a column, a head on the column, means for adjusting the head relatively to the column, a manually controlled member, means extensibly connected to the member for moving the member relatively to the head to control the operation of the machine, and means for maintaining the member in constant relation to the head when the head is adjusted.

2. In a power-operated machine, a column, a head on the column, means for adjusting the machine head vertically on the column, a trip rod, a treadle extensibly connected to the trip rod, and means for maintaining the trip rod in constant relation to the head when the head is being adjusted vertically.

3. In a stopping mechanism, the combination of a power-operated brake for stopping the machine, a trip rod for releasing the brake when the machine is to be started, a collar on the rod, a spring above the collar adapted to depress the trip rod, a spacing member between the spring and the machine frame, an arm fixed on the rod and adapted to engage a stop, and an adjustable stop for limiting downward movement of the rod under the impulse of the spring.

4. In a power-operated machine, a column, a head adjustable on the column having a power driven shaft and an operating instrumentality actuated thereby, a stop mechanism for arresting rotation of the shaft at a predetermined point in its rotation, a treadle, a trip rod, a releasable connection between the treadle and trip rod, a spring for depressing the trip rod, and means for maintaining the spring under tension when said connection is released to allow the head to be adjusted, said means being constructed and 75 arranged to maintain the rod in constant relation

to the head when the head is being adjusted.

5. In a stopping mechanism the combination of a power-operated brake for stopping a machine, a trip rod for releasing the brake when the machine is to be started, a collar on the rod, a spring above the collar for depressing the trip rod, a spacing member between the spring and the machine frame having a sliding fit on the rod, an arm fixed on the rod, and an adjustable stop for limiting the downward movement of the rod under the impulse of the spring.

6. In a stopping mechanism, the combination of a power-operated brake for stopping the machine, a trip rod extending through a hole in the machine frame, means for operating the rod to release the brake when the machine is to be started, a collar on the rod, a spring above the collar, and a spacing sleeve having a sliding fit on the rod and a conical upper end engaging the hole in the machine frame to centralize the rod in the hole.

7. In a stopping mechanism, the combination of a power-operated brake for stopping the machine, a trip rod for releasing the brake when the machine is to be started, a collar on the rod, a spring above the collar for depressing the trip rod, a sleeve located between the spring and the machine frame, said sleeve having at its lower end a frame-like portion contacting with the spring, an arm fixed on the rod within said frame-like portion, and an adjustable stop for limiting downward movement of the rod under the impulse of the spring.

8. In a stopping mechanism, the combination of a power-operated brake for stopping the machine, a trip rod for releasing the brake when the machine is to be started, a collar on the rod, a spring above the collar for depressing the trip rod, a spacing sleeve between the spring and the machine frame, said spacing sleeve contacting at its lower end with the upper end of the spring, an arm fixed on the rod, the free end of the arm having a slot adapted to receive a pin secured to the frame, and an adjustable stop for limiting downward movement of the rod under the impulse of the spring.

9. In a stopping mechanism, the combination of a power-operated brake for stopping the machine, a trip rod for releasing the brake when the machine is to be started, a collar on the rod, a spring above the collar for depressing the trip rod, a spacing member between the spring and the machine frame, an arm fixed on the rod, said arm having a slot-and-pin connection with the frame of the machine, and an adjustable stop for limiting downward movement of the rod under the impulse of the spring.

10. In a stopping mechanism, a combination of a power-operated brake for stopping the machine, a trip rod for releasing the brake when the machine is to be started, a collar on the rod, a spring above the collar for depressing the trip rod, a spacing member between the spring and the machine frame, an arm fixed on the rod, said arm having a slot formed in its free end, a pin secured to the frame and adapted to enter into the slot, and an adjusting screw on the arm extending into the slot for limiting downward movement of the rod under the impulse of the spring.

11. In a stopping mechanism, a column, a head vertically adjustable thereon having a power-driven shaft, an operating instrumentality actuated thereby, a stop mechanism for arresting rotation of the shaft at a predetermined point in

its cycle, a treadle, a trip rod, a wedge-shaped end on the trip rod engaging the stop mechanism, a releasable connection between the treadle and trip rod, a spring for depressing the trip rod, and means for maintaining the trip rod against rotation when said connection is released to allow the head to be adjusted.

12. In a stopping mechanism, a column, a head vertically adjustable thereon having a power-driven shaft, an operating instrumentality actu-

ated thereby, a stop mechanism for arresting rotation of the shaft at a predetermined point in its cycle, a treadle, a trip rod, a roll on the stop mechanism, a wedge-shaped end on the trip rod contacting with the roll, a releasable connection between the treadle and trip rod, and means for maintaining said wedge-shaped end in operative relation to the roll when said rod is released from the treadle to permit adjustment of the head.
